CLAIM

The ornamental design for a cabin overhead and passenger service unit, as shown and described.

DESCRIPTION

FIG. 1 is a perspective view of a cabin overhead and passenger service unit showing our new design;

FIG. 2 is a bottom view of the cabin overhead and passenger service unit of FIG. 1;

FIG. 3 is a left view of the cabin overhead and passenger service unit of FIG. 1;

FIG. 4 is a right view of the cabin overhead and passenger service unit of FIG. 1;

FIG. 5 is a close-up perspective view of a portion of the cabin overhead and passenger service unit of FIG. 1; and, FIG. 6 is a close-up perspective view of a portion of the cabin overhead and passenger service unit of FIG. 1.

The dot-dash broken lines in FIGS. 1, 5 and 6 are for the purpose of annotating the enlargements only and form no part of the claimed design. The cabin overhead and passenger service unit is shown with a symbolic break in its length. The appearance of any portion of the cabin overhead and passenger service unit immediately following the break lines, as well as the break lines themselves, form no part of the claimed design. The dashed lines immediately adjacent the shaded surfaces depict the bounds of the claimed design, whereas all remaining dashed lines depict portions of the cabin overhead and passenger service unit, all of which form no part of the claimed design.

1 Claim, 6 Drawing Sheets
